(57) **CLAIM**

The ornamental design for a base for kamado firebox, as shown and described.

DESCRIPTION

FIG. 1 is a perspective view of the base for kamado firebox; FIG. 2 is a front view thereof; FIG. 3 is a rear view thereof; FIG. 4 is a top view thereof; FIG. 5 is a bottom view thereof; and, FIG. 6 is a right side view thereof, the left side view being a mirror image of the right side view shown. The dashed broken lines in FIGS. 2, 3, 5 and 6 depict environmental subject matter only and form no part of the claimed design. The dot-dot dash broken lines in FIGS. 1, 2, 3, 5 and 6 are boundary lines representing the lower bounds of the claimed portion of the design.
